ADJUSTABLE TENSIONING WEIGHT FOR THE LACE THREAD IN THE LACE BONE OR BOBBIN

Original application filed June 12, 1930, Serial No. 460,743, and in Hungary February 18, 1930. Divided and this application filed March 28, 1931. Serial No. 526,028.

The invention relates to adjustable tensioning weight for the lace thread in the lace bone or bobbin and is a division of our co-pending application No. 460,743.

Tensioning weights are already known, wherein a thread guiding roller is provided for the purpose of reducing the friction on the thread, and also such having a release eyelet, but in their case the thread guide roller and the release eyelet are free so that as the thread is being drawn off it rubs against the bobbin, thus producing a sharp edge thereon which in time severs the thread. This disadvantage is eliminated in the case of the tensioning weight according to the present invention as in this case the thread guiding roll and the releasing bolt are arranged within a U shaped housing, the upper arcuate edge of which raises the bobbin in such a manner that no sharp edge can possibly form thereon. A further advantage of the invention is to be found therein, that the tension of the spring can be regulated by means of a pin pushed through a hole drilled crosswise through the shaft, so that it is not necessary to change the weights according to the quality of the threads, but only the tension of the spring.

An embodiment of the invention is shown as an example on the accompanying drawings, in which Figure 1 shows the adjustable tensioning weight of the bobbin of the rope or string braiding machine as a front view and Fig. 2 is a side view of the tensioning weight without a spring, whereas Fig. 3 is a top view of the adjustable tensioning weight.

The adjustable tensioning weight of the bobbin or the braiding machine consists of a head *a* of a square cross section provided at its lower face with a downward cylindrical shank or shaft. This shank is reduced at two places *b*, *b*₁, each reduced part having a transverse hole *d*, a spiral spring *f* being coiled around the part *b*₁. The top extremity of the spring is fixed by means of a pin pushed through the top hole *d* to the shaft *b* or *b*₁, whilst the lower extremity of the spring is formed into an eyelet or loop *h*. According to whether a stronger or weaker spring is used, in which the inner diameter of the

pitch of the spring is greater or smaller, the top end of the spring is fixed by means of the pin *g* to the thickest part *b* or to the thinnest part *b*₁. A second pin *g*₁ which is inserted into one of the holes below the top hole serves the purpose of regulating the tension of the spring. A cavity is provided in the head *a* of square cross section, whilst two opposite sides and the top part thereof is open. In the interior of the head there is a roller *i* which is rotatably fixed on a riveted in bolt *j*. A second bolt *k* is riveted in above the pin *j*, an opening being left between this bolt and the edge of the roller *i* which makes it possible to insert a lifting hook under the bolt *k* and thus to lift the weight. The top side of the head *a* is arcuated in shape.

The yarn or thread coming from the wooden yarn bobbin (toothed bobbin) is threaded in the usual manner in the bobbin of the yarn braiding machine, and is passed through the cavity in the head *a* of the adjustable tensioning weight arranged in the bobbin of the braiding machine in such a manner, that the threads lie in the groove of the roller *i* whilst the free end of the threads is gripped by the stripper of the braiding machine. When heavy tensioning weights are used, a clamp is provided at the top of the bobbin which prevents the bobbin rising when the thread runs off from the bottom. As is well known the threads are kept tensioned by the weight. The grinding, sliding friction of the thread is eliminated by the roller *i*, as the thread rotates the roller around the pin *j*, thereby preventing any sliding or slipping of the thread, and this circumstance makes it possible to considerably increase the revolution of the machine without any danger of tearing the thread. The design of the adjustable tensioning weight according to the invention presents besides the above mentioned also still further advantages. It was a known deleterious cause inherent to the hitherto known and used tensioning weight that the dust and dirt penetrated when the spring was being tensioned between the separating turns of the spring, into the interior thereof, and settle there and influence the action of the spring deleteriously. The entry of this dirt is pre-

vented by the shaft *b*, which at the same time also acts as a guide for the spring. The holes provided in the shaft *b* and the pin *g*₁ pushed through them makes it unnecessary to have to exchange the weights to suit the quality of the threads. The tension of the spring can be altered by inserting the pin *g*₁ into one or the other of the holes *d*, thus obviating the necessity of exchanging the weights of the spring. If it is notwithstanding required to exchange the springs, then this can be effected without altering the weights, as the stouter spring can be fixed to the stouter portion of the shank *b* and the weaker spring to the thinner portion of said shank *b*. Finally the pin *k* serves also for the purpose of enabling the adjustable tensioning weight to be easily lifted out of the interior of the bobbin of the braiding machine by means of this pin or trunnion. To achieve this purpose the head *a* is rounded off at the top, so that it can freely accommodate the bobbin above it.

We claim:—

- 25 Adjustable thread tensioning device with a thread guiding roller for bobbins of braiding and lacing machines characterized by the fact that the tensioning weight is provided with a forked U shaped head (*a*) open at the top, 30 in which both the rotatably fixed thread guiding roll (*i*) as well as the lifting bolt (*k*) is mounted, the top edges of said head being rounded off in an arcuate manner, and that it is provided with a shaft (*b*) provided with 35 several crosswise holes (*d*), the spiral spring (*f*) being guided on said shaft and being fastened to a pin (*g*) inserted in the top hole, the tension of said spring being adjustable by means of a second pin (*g*₁) by inserting it 40 into one or the other of said holes, according to requirements.
